UNITED STATES PATENT OFFICE.

BENNIE E. GAYLORD, OF LAKEWOOD, OHIO, ASSIGNOR TO WEYERHAEUSER FOREST PRODUCTS, OF ST. PAUL, MINNESOTA, A CORPORATION OF MINNESOTA.

CRATE OR BOX.

Application filed November 11, 1925. Serial No. 62,263.

This invention relates to crates of a collapsible type for return shipment to the factory or other place from which it has been shipped, and more particularly to a crate 5 peculiarly adapted for shipment of plate glass, although its uses and applications are many and various.

Collapsible crates are not new in themselves, but all have involved constructions of 10 a complicated and expensive nature and most of them have been impractically constructed. In order to overcome the various defects and disadvantages of the prior art, I have devised a crate which may be cheaply 15 constructed, one which may be cheaply and easily manufactured, one which may be manufactured from a minimum amount of lumber, the component parts of which may be readily and quickly assembled, secured 20 together, and shipped without danger of damage or breakage to the articles shipped therein, and one which, at its destination, may be easily unpacked with the utmost 25 facility, resolved into its component parts and returned at a minimum of expense to its original point of shipment.

One object of the invention, therefore, is to provide a crate construction which will be cheap to manufacture but strong and durable in use, the while providing 30 constructional features of extreme simplicity.

Another important object is to provide a 35 crate construction in which the top, bottom, sides and ends cooperate in interlocking engagement when assembled, to insure a substantially rigid structure so that pressure from either side from the top, bottom, or ends, tending to urge these portions of the 40 crate inwardly and to crush the contents, will be resisted, not only by these portions of the crate themselves but by the adjacent portions.

A further object of the invention resides 45 in the provision of separable portions or sections of the crate, i. e., top, bottom, sides, and ends, constructed in the manner above set forth to provide a rigid structure and so that when the crate has reached its destination on a shipment it may be quickly unpacked, disassembled, packed into a small 50 space, and returned to the factory or other place from which the shipment was made.

A still further object is to provide a crate 55 of the character above specified, the several sections of which may be assembled and held

in assembled relation without the use of 60 nails, screws, bolts, or the like, if desired, at the option of the shipper or user. In this connection the crate in its preferred form has its component portions or sections secured together by means of bands of metal, 65 wire straps, or the like, which may be cut and removed at the destination and replaced with a new binding on re-use.

Many other objects of importance and 70 other objects including the details of construction should be readily appreciated after the perusal of the specification and claims and after viewing the drawing in which:

Fig. 1 is an isometric view of a crate 75 constructed in accordance with one form of my invention,

Figs. 2, 3, and 4 are top plan, end elevational, and side elevational views respectively of the top and bottom sections of the 75 crate,

Figs. 5, 6, and 7 are top, end elevational, and side elevational views respectively of one of the side sections, and

Figs. 8, 9, and 10 are similar views of one 80 of the end sections.

The crate is composed of top and bottom sections identical in construction, one with the other, two side sections also identical in construction, one with the other, and two end sections also identical in construction, one with the other. For this reason, a description of a top section, of a side section, 85 of an end section and their several features of construction and assembly will suffice. 90

Top and bottom sections.

These sections are each composed of a plurality of parallel longitudinal members 2, 3, 4, 5, and 6, preferably of uniform thickness, spaced apart a slight distance, as shown in edge abutting relation, if desired, and connected or secured in this relation by transverse bars 7, 8, 9 and 10, preferably 100 equally spaced, one from the other, of any suitable or desired number and connected with the members 2 to 6 inclusive through the intermediary of nails, screws, or the like. The two outside members 2 and 6 are made shorter than the interior members 3, 4, etc., as is clearly shown in Fig. 2, and arranged in connection with the interior members which are all flush at their ends, one with another, to provide equal 105 offset shoulders at their ends between the 110

line of their ends and the line of the ends of the interior members. The purpose of this construction will hereinafter appear. Bars 7 to 10 inclusive are of such length that they will overlap the outside edges of the outer members 2 and 6 to provide shoulders for a purpose which will also herein-after appear, and the two outside bars 7 and 10 are arranged with their outside edges flush with the ends of the interior members 3, 4, etc.

The side sections.

Each side section is composed of longitudinal members 11, 12, 13 and 14, preferably of even length and arranged similarly to the members 2 to 6 inclusive of the top and bottom sections, with the exception that their ends are arranged flush, one with the other. These members are likewise connected together by transverse and parallelly arranged bars, 15, 16, 17, 18, 19, 20, 21 and 22, all of which, with the exception of the outer or end bars 15 and 22, are of such length to fall short of the outer sides or edges of the outer members 11 and 14, a distance equal to the thickness of the members 2 and 6 of the top and bottom sections, but the two end bars 15 and 22, arranged with their outer edges flush with the ends of the members 11 to 14 inclusive, extend to the outside edges of the outer members 11 and 14 for a purpose which will herein-after appear. Preferably also the two end bars 15 and 16, and 21 and 22, are spaced from one another longitudinally of the members 11 to 14 inclusive, a distance equal to the thickness of the longitudinal members of the end sections to be herein-after described.

40

End sections.

Each end section is composed of longitudinal members 23, 24, 25 and 26, of equal length and joined together with their ends in alignment by means of two or more transverse bars 27 and 28, in a manner similar to the manner of joining the parts of the top, bottom, and side sections. In these sections, however, the transverse members 27 and 28 not only are arranged to overlap the outer sides or edges of the outer members 23 and 26 to provide shoulders of a depth equal to the depth of the members 2 and 6, but are spaced from the respective ends of the members 23 to 26 inclusive to provide shoulders therebetween of a depth equal to the thickness of the bars 15 and 22.

Assembly.

With the several sections constructed as above specified, the crate is ready for assembly which is accomplished in the following manner: The bottom section is laid down with the transverse bars lowermost, the end sections placed thereon with the

ends of the bars 27 resting on the tops of members 7 and 10 and abutting against the ends of members 2 and 6, and while these sections are temporarily supported, the side sections are set upon the ends of members 7 to 10 inclusive, and the ends of the members 23 to 26 inclusive engaged in the slots formed between the bars 15 and 16 and 21 and 22 of the side sections thereof. When this has been accomplished, the members 11 to 14 inclusive abut against the ends of members 23 to 26 inclusive, while the interior face of the bars 15 and 22 abut against the outer edges of bars 27 and 28 and the interior faces of the members 23 to 26 inclusive abut against the adjacent edge of the bars 16 and 21. The top section is then placed upon the assembled sides, ends, and bottom and interlockingly engages with the sides and ends in the same manner in which the bottom engages them. It should be noted particularly that the transverse bars of the top and bottom sections are arranged to be on the outside of the crate assembly and to extend in the same direction with one another at similar points of the assembly structure, i. e., top and bottom bars, 7, 8, 9, and 10, are relatively arranged in the same positions with respect to the crate. Thus steel or other metal bands 30, 31, 32 and 33 may be secured about the structure against the outer faces of the members 11 to 14 inclusive along the length of the bottom faces of the bars 7 to 10 inclusive and along the length of the faces of the top bars 7 to 10 inclusive.

Metal straps, such as those referred to in the foregoing paragraph, may be readily purchased on the open market at nominal cost, and for this reason, when the crate has reached its destination, these straps may be cut or otherwise destroyed and new ones used to replace them on re-use of the crate. After the crate has been opened at its destination and its contents removed, the several sections may be secured together in any suitable manner and, in their collapsed condition, assembled into a very small space, as will be obvious, for return shipment to the manufacturer or other point of origination of shipment. This feature enables the crate to be used over and over again, effecting great economy in lumber and manufacturing costs, while the slight cost of return shipment is negligible.

It will also be appreciated that pressure tending to urge the top and bottom sections toward one another intermediate the ends thereof will be resisted by engagement of the the outside members of the top and bottom sections abutting against the ends of the bars of the side sections and by abutting engagement of the bars of the top and bottom sections against the edges of the outside members of the side sections, while pressure

at the ends of the top and bottom sections will be resisted by abutting engagement of the members and bars of the top and bottom sections against the members and bars respectively of the end sections. Any pressure tending to urge or collapse the side sections toward one another will be effectively resisted by abutting engagement of the outside members of the side sections against the outside edges of the outside members of the top and bottom sections and by abutting engagement of the members of the side sections against the outside edges of the bars and the ends of the members of the end section. Pressure tending to urge the end sections toward one another or inwardly of the crate will be resisted by abutting engagement of the members of the end sections against the transverse bars 16 and 21 of the side sections and by the transverse bars of the end section engaging the ends of the outside members of the top and bottom sections. Relatively enormous pressure may be placed upon the top, bottom, and sides of the crate I have devised without danger of breakage or damage to goods shipped within. The transverse bars of the top and bottom serve as additional guards against damage to these sections and with the end sections inset from the ends of the top, bottom, and side sections, little, if any, danger of breakage may be expected in this direction.

Many variations or modifications may be made within the spirit of the invention which will clearly fall within the purview of my contribution. For this reason I do not desire to be limited to the details of construction or to the form of the invention shown and described for illustrative purposes only, but only by the spirit of the invention and the scope of the appended claims.

I claim:

1. A crate comprising; top and bottom sections, each composed of a plurality of parallel and adjacent longitudinal members, the two outside members terminating short of the ends of the interior members, and a plurality of longitudinally spaced transverse bars each extending laterally beyond the sides of said outside members and the two outside bars each secured with their outside edges flush with the ends of said interior members; side sections, each composed of a plurality of parallel and adjacent longitudinal members of even length, and a plurality of longitudinally spaced transverse bars, the two end bars being flush at one side with the ends of said longitudinal members and being flush at their respective ends with the sides of the outside longitudinal members, and the intermediate bars terminating short of the outside edges of the two outside longitudinal members; and end sections, each composed of adjacent

parallelly disposed members of even length, and a plurality of transversely disposed bars of which the end bars are spaced from the ends of said members and extend beyond the outer sides of the outside members. 70

2. A crate comprising; top and bottom sections, each composed of at least three adjacent members with the outside members terminating short of the ends of the interior members, and a plurality of transverse bars 75 of even length each extending laterally beyond the outer sides of the outside members and the outside bars having their outside edges flush with the respective ends of the interior members; side sections, each composed of a plurality of adjacent longitudinal members of even length and at least three transverse bars, two of said bars being disposed one across each composite end of said members and substantially flush at one side 80 and both ends with the ends and sides respectively of the composite ends, the intermediate bar or bars terminating short of the outer sides of the outside members; and end sections, each composed of adjacent members 85 of even length and a plurality of transversely disposed bars, of which one bar is placed adjacent each composite end of said members but spaced therefrom. 90

3. A crate comprising; top and bottom sections, each composed of at least three adjacent members with the outside members terminating short of the ends of the interior members, and a plurality of transverse bars of 95 even length each extending laterally beyond the outer sides of the outside members and the outside bars having their outside edges flush with the respective ends of the interior members; side sections, each composed of a plurality of adjacent longitudinal members of even length and at least three transverse bars, two of said bars being disposed one across each composite end of said members and substantially flush at one side and 100 both ends with the ends and sides respectively of the composite ends, the intermediate bar or bars terminating short of the outer sides of the outside members; and end sections, each composed of adjacent members of even length and a plurality of transversely disposed bars, of which one bar is placed adjacent each composite end of said members but spaced therefrom. 105 said top and bottom, side and end sections being constructed and arranged to be assembled in interlocking engagement one with the others, with the bars of the side sections interior and the bars of the top and bottom sections exterior of the crate structure. 115

4. A crate comprising; top and bottom sections, one of said sections being composed of at least three adjacent members with the outside members terminating short of the ends of the interior members, and a plurality 120 of transverse bars of even length each ex- 125

tending laterally beyond the outer sides of the outside members and the outside bars having their outside edges flush with the respective ends of the interior members; side sections, one of said sections being composed of a plurality of adjacent longitudinal members of even length and at least three transverse bars, two of said bars being disposed one across each composite end of said members and substantially flush at one side and both ends of said bars being disposed one across each composite end of said members and substantially flush at one side and both ends with the ends and sides respectively of the composite ends, the intermediate bars terminating short of the outer sides of the outside members; and end sections, one of said sections being composed of adjacent members of even length and a plurality of transversely disposed bars, of which one bar is placed adjacent each composite end of said members but spaced therefrom.

5. A crate comprising; top and bottom sections, each composed of at least three adjacent members with the outside members terminating short of the ends of the interior member or members, and a plurality of transverse bars of even length each extending laterally beyond the outer sides of the outside members and the outside bars having their outside edges flush with the respective

ends of the interior member or members; side sections, each composed of a plurality of adjacent longitudinal members of even length and at least three transverse bars, two of said bars being disposed one across each composite end of said members and substantially flush at one side and both ends with the ends and sides respectively of the composite ends, the intermediate bar or bars terminating short of the outer sides of the outside members; end sections, each composed of adjacent members of even length and a plurality of transversely disposed bars, of which one bar is placed adjacent each composite end of said members but spaced therefrom, said top and bottom, side and end sections being constructed and arranged to be assembled in interlocking engagement one with the others, with the bars of the side sections interior and the bars of the top and bottom sections exterior of the crate structure, and replaceable bands, for securing said sections in assembled relation, about said top, bottom and side sections, extending along said bars on the top and bottom sections.

In witness of the foregoing I affix my signature.

BENNIE E. GAYLORD.
